UNITED STATES PATENT OFFICE

CLAIBORN CLARK, OF LOS ANGELES, CALIFORNIA

RAILWAY CROSSING

Application filed August 27, 1929. Serial No. 388,691.

This invention relates to railway equipment and more especially to intersecting track-ways where flanged car wheels cross intersecting tracks.

It is well known that a great deal of seriously objectionable noise is caused where the treads of wheels jump over gaps necessarily provided at all intersections where flanged wheels must pass in traffic.

Various divers means have been proposed for rendering car crossing tracks quiet or silent but the principal objection to most such proposed mechanisms is undesirable complications of apparatus, and unreliabilities of operation, coupled with fragility of parts.

It is therefore an object of my present invention to provide an automatic silent crossing track mechanism with extreme simplicity as one of its principal characteristics.

A further object is to provide in combination with a crossing track system, a set of co-acting and synchronized gap bridgers which are operative with a minimum degree of stroke and which are positively limited at respective positions by opposed, directly engaged buttresses.

A further object is to provide a safety device to compensate for inequalities in depths of flanges of various wheels which may operate over the silencing mechanism.

Other objects, advantages and details of means and features will be made manifest in the ensuing description of the herewith illustrative embodiment; it being understood that modifications, variations and adaptations may be resorted to within the spirit, scope and principle of the invention as it is more directly claimed hereinafter, and which consists of the disclosure and its substantial equivalents.

Figure 1 is a plan of the installed silencing apparatus.

Figure 2 is a vertical section on line 2-2,

Fig. 1.

Figure 3 is a perspective of a gap bridger and its operating lever.

The apparatus is shown as combined with tracks N and S which are alined and with cross tracks W and E, which are alined.

To provide for the passage of wheels X with flanges F the several tracks meet in corner blocks B which have track gaps G paralleling the inner faces of the treads of the several tracks N-S-W-E. 55

Obviously when the treads of the wheels jump the gaps G the impingement of the wheels on the opposed shoulders of the blocks produce highly objectionable noise. The present invention consists of means whereby 60 to fill the gaps occurring at the intersection along the tracks over which wheels may be passing. It is desirable to provide such means with the utmost of simplicity and with a minimum degree of movement of necessary 65 operating means.

Therefore each block B is provided with a diagonal countersunk slide 2 having a widened central body 3 which is slidably guided and retained under over-hanging 70 ledges B' whose top faces are flush with the track treads and the tops of the blocks B.

The central body 3 of the slide 2 is provided with a triangular body 4 forming a filler or bridger whose top face 5 is flush with the treads of the tracks. This bridger is arranged with its apex 6 inwardly disposed and its right angular side faces 7 and 8 are adapted to bear against stop shoulders S and S' formed by the inner corners 75 of the block spaces G with which the spacing bridger 5 is registerable alternately.

Each bridger slide is provided with a lever arm 10 having a vertical pivot 11 from which extends an arm 12 with a down turned shank 13 having a clevis part 14. In the system, the several lever arms are arranged diagonally as to the intersection and each clevis is attached to a pair of links 15 and 16 which lie at right angles to each other and extend outwardly to respective actuating mechanism. 85

Such mechanism consists of a set of rock-shafts 20 and 21 for the N and S tracks, and a rock-shaft 22 for the W track and a rock shaft 23 for the E track. 90

The rock shaft 20 has lever arms 24 to which are connected parallel links 15 and the rock shaft 22 has lever arms 25 to which are connected the links 16. Rock-shaft 23 has 100

lever arms 27 to which are connected links 16' from respective clevises and rock-shaft 21 has lever arms 28 to which are connected links 15' from respective clevises.

5 Suitable means are provided to operate each rock-shaft by the action of a pair of twin wheels X approaching the intersection from a direction relative to each particular rock-shaft.

- 10 The mechanisms for actuating the several rock-shafts are composed of identical devices which, each, include a treadle 30 having elongated slot 31 receiving a trunnion 32 on which the treadle is mounted, one along the inside of each track in such position as to be engaged by a flange F of a traveling wheel X. The normal effective position of each treadle 30 is with its inner end upward and in the path of wheel flanges. Since the flanges may project various distances below the track tread the treadles 30 have rollers 32 in their lower outer corners which are adapted to shift on bearing plates 33 provided therefore to positions determined by the depression stroke of the treadle under flange action.

20 Each treadle 30 is connected by a link 34 to a short lever arm 35 fixed on the respective rock-shaft as 23, Fig. 2.

25 The operation is therefore, as follows: As a car approaches the intersection its front wheels X will engage and simultaneously depress the treadles 30, if they are in upper position, which will be the case when the bridgers 5 are in such position as to obstruct the passage of the flanges into and across the gaps G in direction of travel of the approaching car. On the other hand, if the gaps G, in line of travel are open then the treadles of the related open gaps are in down or lower positions so that the car wheels pass without effect on the treadles.

30 All of the treadles 30 are combined through the several links and their lever arms 12 so that the treadles act synchronously. The treadles of the W and E tracks are positioned to be all simultaneously up or all down. That is, all of these treadles will be in upper position when the bridgers 5 close the respective gaps G, or they will be down if the gaps are open, while the treadles 30 of the tracks N and S are in the opposite relation or position and are up while the other treadles are down and vice versa.

35 When the treadles of a cross track are depressed the related bridgers of that track will shift into alinement to fill the lateral gaps in wheel path so that the wheel treads pass onto and over the bridgers without material noise.

40 The stroke necessary is just enough to shift the bridgers in a short diagonal path from one buttress S to its diagonally opposite relative which form positive stops for the actions.

45 Thus a car approaching on the N tracks, Fig. 1, will depress the raised treadles 30 and through the links 15 will oscillate all of the

levers 12 and these will in turn shift the bridges 5 to open the gaps G in the N-S tracks so that wheels can run through free while the treads of the wheels will pass onto the bridgers which have therefore been shifted into the line of travel of the wheels treads on the N-S tracks. Such action raises the treads of the W-E tracks so that when a car approaches on either of these, the treads will be in position for action and function to shift the interposed bridgers out of the way and into bridging position for the wheels running on W and E tracks.

50 The semi-floating capacity of the treads is a safety feature allowing for relief of resistance and tension of parts in event a deep flange rolls over any treadle.

55 It will be noticed that only a small area of the slide is flush with the track treads and that area is the top of the small bridgers 5. Any dirt collecting in the path of the bridger action will be worked out into the clearance gaps.

60 What is claimed is:

1. A sound-reducing railway crossing including a set of blocks with right angular flange gaps for passing wheel flanges, diagonal slides in said blocks having triangular bridgers shiftable diagonally at the intersection of the gaps of respective blocks to close the gaps in line of wheel passage a diagonal lever pivoted on each block and connected to its slide, and treadle actuated means connected to the levers.

65 2. A sound-reducing railway crossing including a set of blocks with right angular flange gaps for passing wheel flanges, diagonal slides in said blocks having triangular bridgers shiftable diagonally at the intersection of the gaps of respective blocks to close the gaps in line of wheel passage, rock shafts with pairs of treadles at each trackway, and a radial lever pivoted, on each block, connected to its slide and also to relative rock shafts of intersecting trackways.

70 3. In a railway crossing structure a gap bridging device including a slide, and a block in which it is countersunk; said block having a stepped down inner corner, and a slide actuating lever pivoted on said corner.

75 4. In a railway crossing structure a gap bridging device including a slide, and a block in which it is countersunk; said slide having a triangular bridger on its top to alternately fill intersecting flange gaps in the block, and an inwardly radiating arm pivoted on the block and connected to the slide.

80 5. In a railway crossing structure a gap bridging device including a slide, and a block in which it is countersunk; said slide having a triangular bridger on its top to alternately fill intersecting flange gaps in the block, and a radiating arm pivoted on the block system of right angularly disposed treadle shafts and connections between such arm and two

of said shafts which are at a right angle to each other.

6. In a railway crossing structure a system of treadle levers one at each track rail intersection, crossing blocks having intersecting flange gaps, and a system of bridgers diagonally operative between the gaps of respective blocks, stop means engaging faces of the bridgers, treadles for each rail from or to the intersection, and means connecting each bridger with treadles and levers relative to intersecting trackways.

7. In a silent track crossing apparatus, a treadle operated mechanism including a semi-floating treadle, a trunnion on which it is slideable and tiltable, and a foot bearing on which the lower end of the treadle is rollable according to its actuation by wheel flanges.

8. In a track crossing, a quadrangle of rock shafts each having treadles at its ends adjacent to rails of a relative crossing trackway, crossing blocks having intersecting gaps at the junction of the rails, gap bridgers in said blocks, levers pivoted on the blocks and connected to the bridgers and radiant to the quadrangle, and links connecting each lever to a respective pair of the shafts at its corner of the quadrangle.
